UNITED STATES PATENT OFFICE.

ALBERT ISIDORE FROMAGER AND JOSEPH FERDINAND SIX, OF MONTREAL, QUEBEC,
CANADA.

SWITCH-BLOCK AND CASING.

1,223,378.

Specification of Letters Patent.

Patented Apr. 24, 1917.

Application filed May 10, 1916. Serial No. 96,728.

To all whom it may concern:

Be it known that we, ALBERT ISIDORE FROMAGER and JOSEPH FERDINAND SIX, both subjects of the King of Great Britain, and residing at Montreal, Province of Quebec, Canada, have invented certain new and useful Improvements in Switch-Blocks and Casings; and we do hereby declare that the following is a full, clear, and exact description of the invention, such as will enable others skilled in the art to which it appertains to make and use the same.

The present invention relates to improvements in switch blocks and casings such as that shown and described in our copending application filed May 14, 1915, Serial Number 28,197.

The object of the present invention is to provide a switch block of the character aforesaid wherein a more positive contact will be made between the switch members and the device will be more simple, durable and efficient in construction and operation and one which will have less parts, reducing the cost of manufacture thereof and making the article of more commercial value.

A further object of the invention is to provide a fool-proof casing for switch blocks of this character wherein only authorized persons are permitted to gain access to the interior thereof and a slideable door for the said casing which automatically controls the switch whereby when the said door is opened the switch will be opened and when the door is entirely closed the switch is closed to establish the circuit.

With the above and other objects in view which will hereinafter appear as the description continues, the invention consists of the novel features of construction and the formation of parts as will be hereinafter more fully described and particularly pointed out in the appended claims.

In the accompanying drawings is shown a simple and preferred form of the invention it being, however, understood that no limitation is necessarily made to the precise structural details herein exhibited but the right is hereby reserved to any changes or alterations that may be made that come within the scope of the invention without departing from the spirit thereof or sacrificing the efficiency of the same.

Figure 1 is a plan view of the casing hav-

ing the switch block arranged therein as 55 embodied in the present invention;

Fig. 2 is a similar view with the cover of the casing removed;

Fig. 3 is a side elevation of the switch block;

Fig. 4 is a vertical longitudinal section taken on the line 3—3 of Fig. 2 and showing a portion of the switch block in section;

Fig. 5 is a vertical longitudinal section through the switch block when the switch is 65 closed;

Fig. 6 is a front elevation of the switch block;

Fig. 7 is a vertical transverse section with the fuse plugs removed taken on the line 70 7—7 of Fig. 5;

Fig. 8 is a detail end section of the cover; and,

Fig. 9 is a detail plan view of one of the bushings; and,

Fig. 10 is a detail plan view.

Referring now more particularly to the drawings wherein like and corresponding parts are designated by similar reference characters throughout the several views— 75

The block 1 is of approximately rectangular configuration made of porcelain or other suitable insulating material. Arranged at one end of the block is a raised portion 2 having a pair of threaded sockets 3 formed 85 therein in which are adapted to be placed the fuse plugs for a purpose which will be later described. Extending longitudinally through the base portion of the block 1 are a pair of parallel extending bores each 90 of which having mounted in one end thereof a bushing 3 and these bores having mounted in their opposite ends the bushings 4 and the bushings arranged within each bore are held in spaced relation with each other thereby providing a spaced portion 5 in each bore. Contacting with each of the bushings 4 is a brass screw 6 to which are connected the wires 7 and through which the current is supplied from the main line to the connections within the fuse block and subsequently carried to the meter. This meter may be in circuit with a lighting system or any other electrical system arranged within the house to which current is to be supplied. Encircling each of the bushings 3 and held in positive contact therewith are the rings 8 each having a bushing 9 formed integral there-

with and these bushings extend upwardly within openings formed within the base block 1 and terminating within the sockets 3. Adapted to be arranged within each of the sockets 3 is a fuse plug socket 10 of suitable conducting material each of which is adapted to be connected to the arms 9 by means of the set screws 11. Extending from each of the sockets 10 is a plate 12 to which are connected the wires 13 by means of an ordinary electrical connection 14. Adapted to be arranged within the fuse sockets 10 are fuses 15 being of the ordinary and well-known construction. Slidably mounted within each of the bushings 3 is a rod 16 having their outer ends bent upwardly and connected to an insulated block 17.

By this construction it is obvious that the flow of current will pass through the wires 7 into the sleeves 4 and after the switch has been closed the current will pass through the wires 13 into the meter indicated by the numeral 38 and from the meter the current passes through the wires 34 to any suitable system.

To hold the rods 16 in positive contact with the bushings 3 we provide leaf springs 18 which are rigidly connected at one end to a sleeve 19 carried by each of the bushings 3 and the opposite or free ends of the leaf springs 18 rest within openings 20 formed within the bushings 3 and press against the rod 16 thereby holding the said rod in positive contact with the inner wall of the sleeve 3.

From the foregoing construction it is also obvious that when the inner ends of the rods 16 are within the bushings 3 the circuit will be broken and the inner ends of the rods 16 will have to pass through the space 5 within the bores before closing the circuit and the circuit will not be closed until the inner ends of the rods 16 engage with the bushings 4.

The switch block is adapted to be mounted within a fool-proof casing made of metal or suitable material and is properly insulated therefrom. This casing comprises substantially a rectangular box 21 having a cover 22 therefor. The switch block is also detachably secured within the casing by means of the screws 23 as better shown in Fig. 2 so that the block will be held in proper position and prevented against movement and the casing may be suitably secured in any well known manner to a wall or suitable support. A door 25 having one end connected to the block 17 by means of a screw or other suitable fastener extending through the door into the threaded recess 24 arranged within the block 17 and its opposite end is provided with an undetectable knob 26 whereby the door may be manually operated and when so operated is adapted to cause the block 17 to reciprocate thereby moving the rods 16 for

opening and closing the switch. The door 25 is adapted to operate within the casing 21 and the knob 26 passes through an elongated slot 27 formed within the cover 22. This slot 27 is provided with a transversely extending portion 28 which exposes the fuse plugs to view when the door 25 is opened.

From the foregoing it will be seen that when the door is opened the switch will also be opened and the circuit broken and the fuse plugs 15 will be exposed so that should any of the fuse plugs be burned out new ones may be substituted therefor. Also arranged within the casing 21 is a partition 29 having its lower end adapted to rest within a recess 30 arranged within the block 1. This partition prevents access from being gained to the wires 7 or permitting unauthorized persons from stealing electric current.

The wires 7 extend through a bushing 31 formed within one end of the casing 21 whereas the wires 13 project through the side of the casing 21 and are hidden from view by means of the casing 32 secured to one side of the casing 21. The wires 34 may extend from the meter or from the casing 32 either at the side of the latter as shown within the drawings or from any end thereof, but the casing 32 incloses the wires 13 and the connection between the same and the meter 38 so as to prevent persons from gaining access to the wires 13 after the door 25 has been closed and the switch closed so as to prevent persons from stealing or otherwise taking the current from the wires 13 before it has passed through the meter 38.

The cover 22 has formed within the depending flange thereof at one end of the cover a pair of spaced openings 35 which are adapted to receive lugs 36 carried by the casing 21 for holding one end of the cover upon the casing 21 and the flange at the opposite end of the cover 22 is provided with an opening through which extends an apertured projection 37 to which a padlock, seal or similar locking means may be connected for locking the cover in place and preventing unauthorized persons from gaining access to the interior of the casing 21 or in any manner tampering with the switch. Whereas in the drawings we have shown the switch block having two wires leading therefrom to the meter it is of course to be understood that any number of supply leads may be used as desired.

Having thus fully described our invention, what we claim as new and desire to secure by Letters Patent is:

1. In a device of the character described comprising a casing, an insulated block arranged within said casing, said block having a pair of spaced longitudinally extending bores formed therein, switch terminals arranged within each of said bores, a pair of rods slidably mounted within said bores

for opening and closing said switch terminals, an insulated block for connecting one end of said rods, fuse plugs adapted to be connected in circuit with said switch terminals, said casing having an opening therein whereby access may be gained to said fuse plugs, a partition arranged within said casing to prevent access from being gained to the switch terminals arranged within one end of said bores, a plate slidably mounted within said casing, one end of said plate being connected to said block carried by said rods and means for sliding said plate whereby said rods will cause said switch terminals to be connected after said plate has completely closed the opening within the casing and disconnected said switch terminals before said plate can be permitted to open the opening within the casing.

2. In a device of the character described comprising an insulated block, a pair of parallel horizontally extending bores extending through said block, a pair of bushings arranged within each bore and held in spaced relation, a pair of rods slidably mounted within said bushings for electrically connecting the same, one end of said block having an enlarged portion formed therewith, fuse plugs adapted to be arranged within said enlarged portion, rings encircling the bushings arranged within one end of said block, means for connecting said rings with said fuse plugs, the last mentioned bushings having openings therein, leaf springs carried by said bushings having their free ends adapted to rest within said openings where-

by they may contact with said rods, and means for connecting one end of said rods whereby they may be jointly operated. 40

3. In a device of the character described comprising a casing, an insulated block arranged within the medial portion of said casing, said block having a pair of spaced longitudinally extending bores therein, 45 switch terminals arranged within each end of said bores, rods extending within said bores for connecting said switch terminals, a block for jointly connecting one end of said rods, said insulated block having an enlarged portion, fuse plugs adapted to be arranged within said enlarged portion and adapted to be connected to the switch terminals arranged within one end of said bores, electric connections connected to the switch 50 terminals arranged within the opposite ends of the bores, a partition arranged within said casing for preventing access to be gained to the said electrical connections with the last mentioned switch terminals, a detachable 55 cover for said casing having an opening therein, a slideable plate connected to said rods and adapted to close said opening, and means whereby when said plate is opened the switch terminals will be disconnected 60 and access may be gained to said spark plugs and means whereby after said opening is closed said switch terminals will be connected, substantially as and for the purpose 65 set forth. 70

In witness whereof we have hereunto set our hands.

ALBERT ISIDORE FROMAGER.
JOSEPH FERDINAND SIX.
